CLAIM

The ornamental design for an insertable and detachable deck anchor, as shown and described.

DESCRIPTION

FIG. 1 is a perspective view of the insertable and detachable deck anchor, showing the novel insertable and detachable deck anchor design.

FIG. 2 is a front side view, taken looking at the front of the insertable and detachable deck anchor design.

FIG. 3 is a back side view, taken looking at the back of the insertable and detachable deck anchor design.

FIG. 4 is a left side view thereof.

FIG. 5 is a right side view thereof.

FIG. 6 is a top plan view thereof; and,

FIG. 7 is a bottom plan view thereof.

In the drawing figures, surface shading is used to clearly show the character and contour of surfaces of the 3-dimensional aspects of the design, and form a part of the design sought to be protected.

The broken lines in the drawings illustrate portions of the insertable and detachable deck anchor and form no part of the claimed design.

The characteristic feature of the design resides in the shape of the shaft assembly, including the lower anchor portion, the central longitudinal rod portion, and the upper attachment portion, of the tie-down deck anchor.
